Z. PHINNEY
SCALE.

Patented Jan. 6, 1814.

June 6, 1814
Jina Phinney
Sisters, Patent

The article referred to in the following patent and making part of the same containing a description in the words of the said Jina Phinney him self of his improved Steel Cards or scales.

This machine consists of a weight, a beam, or rod arm and one scale, all of which are described as follows. vizt. The weight may be made of various forms, to answer the same purpose, but I calculate to have it of a conical form, or an angular form as far up it as to the fulcrum on which it is hung: and from it I have a kind of an arm extending upwards in an angle of about 30 degrees altitude. This arm may be varied agreeably to the size of the machine, that is to say, it may be longer or shorter agreeably to the length of the weight, and there is a mortise in the upper end of it to receive the upper end of the rod, which supports and guides them both by side. There may be a second arm to the weight and of a circular form, and attached to it near the bottom end, or it may be attached to the rod and pass through a mortise in the weight, or slip by the side, or under the lower end of the weight, or when attached to the lower end of the weight it may pass by the side of the rod. The circular arm has marks and figures on it, for to show the pounds and ounces. The scale is hung to the lower end of the rod, and whatever is to be weighed being put in it, it tends to pull the rod downwards. It has a tendency to throw the lower end of the weight out of its perpendicular situation, which is the mode of weighing, and by looking at the edge of the weight on the circular arm at the mark or figure on it, you tell the weight of the article in the scale. There can also be two hooks, one for the little side.
